OSCAR L. OWEN, OF WHITINSVILLE, MASSACHUSETTS, ASSIGNOR TO THE WHITIN MACHINE WORKS, INCORPORATED, OF WHITINSVILLE, MASSACHUSETTS.

SHEDDING MECHANISM FOR LOOMS.

SPECIFICATION forming part of Letters Patent No. 757,141, dated April 12, 1904.

Application filed June 30, 1902. Serial No. 113,839. (No model.)

To all whom it may concern:

Be it known that I, OSCAR L. OWEN, a citizen of the United States, residing at Whitinsville, in the county of Worcester and State of Massachusetts, have invented a new and useful Improvement in Shedding Mechanism for Looms, of which the following is a specification.

This invention relates to the class of shedding mechanism for looms known as "dobbies," in which one set of hooked jacks is operated directly by every alternate lever of the set of levers acted upon by the pattern chain or surface and the other set of hooked jacks is operated by the other set of levers.

The object of this invention is to provide improvements in means for operating and controlling the hooked jacks and the levers.

To this end the invention consists in the peculiar and novel construction, as will be more fully set forth hereinafter.

Figure 1 is a vertical section of the dobby, showing one of each of the two series of hooked jacks pivoted on the connector and supported in the raised position above the lifters. Fig. 2 is an elevation of the upper grate, and Fig. 3 is a sectional view of the same. Fig. 4 is an elevation of the lower grate, and Fig. 5 is a sectional view of the same. Fig. 6 is a plan view of the rocker-bar.

In the drawings, $a\ a$ indicate the end frames of the dobby; $d\ d'$, the lifter-bars sliding in the slots $a^2\ a^2$ of the end frames; a^7 , one of the upper series of hooked jacks; a^8 , one of the lower series of hooked jacks; $a^4\ a^4$, the stops; a^5 , one of the series of connectors pivotally secured to one of the upper and one of the lower hooked jacks and to the harness-lever a^6 ; b , the pattern-chain; b' , one of the series of counterweighted levers directly engaging with and supporting the lower series of hooked jacks a^8 , and b^2 one of the series of counterweighted levers for supporting one of the upper series of hooked jacks a^7 by means of the rod c , bent at its upper end to form the bracket c' , which extends into one of the slots in the upper grate and bears on the under side of the hooked jack, the lower end resting on the le-

ver b^2 . The levers b' and b^2 are operated at predetermined intervals by the pattern-chain b or a pattern-surface, a projection of which lifts the overweighted end b^3 of the lever, causing the lever to rock on the pivotal support b^4 and permitting the hooked jack supported by the lever to engage with one of the lifters to operate the harness-lever.

The upper grate d has the slots $d'\ d'$, in which the hooked jacks a^7 of the upper series are guided and separated by the vertical bars d^2 , which extend from the top bar d^3 to the bar d^4 . To securely guide the rods c , I extend the grate below the bar d^4 , curve the bars d^2 , and unite them with the bar d^5 . The rod c may freely move longitudinally in the opening thus formed and is held against lateral movement by the curved bars d^2 and the bars d^4 and d^5 . The bracket c' on the rod extending into the vertical slot in which the jack moves forms an additional guide, which prevents the rod from turning. A round wire rod may be used for the rod c . The grate d , including the guides for the rods c , are cast in one piece. The guides and collars on the rods c are not required, and the cost is materially reduced.

To further economize in the cost of construction, I form the lower grate e and the grate e' , in which the ends of the levers b^2 are guided, in one casting and provide the same with openings in which the lower part of the rod c is guided. As shown in Figs. 4 and 5, the oblique portion e^2 of the grate, having the slots e^3 , in which the hooked jacks a^8 and the ends of the levers b' move, terminates in the cross-bar e^4 . It has the cross-bar e^4 offset and connected with the slotted part e^5 , in which the ends of the levers b^2 move. The bars e^4 and e^5 are placed oblique to each other and are connected by the division-bars d^2 , so that the grate may be cast in one piece and the rods c may be extended through the slots of the oblique part e^5 and rest on the plane ends of the levers b^2 . The grates are respectively provided with the lugs d^6 and e^6 , which fit into sockets formed in the end frames of the dobby.

To conveniently lift the weighted ends of

the levers b' and b'' from the pattern, I provide the end frames α with the lugs $f'f$ and journal in the end frames the lever-bar f' , having the arm f^2 on one end. In the normal condition the lever-bar f' rests on the lugs $f'f$. When it is required to lift the levers off from the pattern, the lever-bar may be rocked on its journal-bearings and all the levers simultaneously raised, as is indicated in broken lines 10 in Fig. 1.

Having thus described my invention, I claim as new and desire to secure by Letters Patent—

1. In a shedding mechanism for looms, the combination with the hooked jacks, a counter-weighted lever for operating one of the jacks direct, a lever for operating the other jack by means of a rod, the rod, and the pattern, of a grate the slotted portion of which has two bars placed oblique to each other to form the supports for the rods supporting the upper jacks, one of said bars also forming a stop to limit the movement of the counterweighted lever, as described.

2. In combination with the jacks, the lifters, the connectors, and the pattern of a shedding mechanism of a loom, of the lever b' operating one of a series of jacks, the lever b'' and the rod c operating one of the other series of jacks, the grate d provided with the bars d^3, d^4, d^5 and the lugs d^6 , and the grate e having bars e^2, e^3 and lugs e^4 , as described.

3. In a shedding mechanism, the combination with the jacks and the levers b' and b'' , of the grate e having the slotted portions e^2 and e^3 formed in one casting, the slotted portion e^6 and the slotted portion e^7 having the cross-bars e^4 and e^5 offset oblique to each other, as described.

In testimony whereof I have signed my name to this specification in the presence of two subscribing witnesses.

OSCAR L. OWEN.
